To all whom it may concern:

Be it known that we, Walter M. Boothby and William Randolph Lovelace, II, citizens of the United States, residing at Rochester, in the county of Olmsted and State of Minnesota, have invented a new, original, and ornamental Design for an Aviator's Oxygen Mask or Similar Article, of which the following is a specification, reference being had to the accompanying drawing, forming part of the specification.

Fig. 1 is a front perspective view of an avia-

tor's oxygen mask or similar article embodying our new design.

Fig. 2 is a rear elevational view of the mask of Fig. 1.

Fig. 3 is a side elevational view of the mask of Fig. 1.

We claim:

The ornamental design for an aviator's oxygen mask or similar article, as shown.

WALTER M. BOOTHBY.
